UNITED STATES PATENT OFFICE

HOYT M. MURPHY, OF HERMLEIGH, TEXAS

TERRACING AND DITCHING MACHINE

Application filed February 3, 1932. Serial No. 590,713.

The invention relates to a road building machine and more especially to a terracing and ditching machine.

The primary object of the invention is the provision of a machine of this character wherein the gathering or scraper blades are so mounted as to permit adjustment thereof for the positioning of the same for either ditching or terracing purposes, the blades 10 being supported in a novel manner and are positioned relative to the ground surface through the medium of controls located fore and aft of the machine and at opposite sides of the same.

Another object of the invention is the provision of a machine of this character wherein the controls for the raising and lowering of the blades relative to a ground surface are properly housed so as to exclude dust and dirt therefrom and thus avoid interference in the easy handling of such controls.

A further object of the invention is the provision of a machine of this character wherein the adjuncts thereof are novel in form so that the machine can be easily and conveniently converted for use as a terracing, ditching or road machine.

A further object of the invention is the provision of a machine of this character which is comparatively simple in construction, thoroughly reliable and efficacious in its operation, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:—

Figure 1 is a top plan view of the machine constructed in accordance with the invention showing the same adjusted for terracing purposes.

Figure 2 is a side elevation thereof.

Figure 3 is a rear elevation.

Figure 4 is a view similar to Figure 1 on

a reduced scale showing the machine adjusted for use in ditching.

Figure 5 is a fragmentary detail vertical sectional view through one of the controls.

Figure 6 is a sectional view on the line 6—6 of Figure 1 looking in the direction of the arrows.

Figure 7 is a detail vertical sectional view through one of the supports for a blade or scraper.

Figure 8 is a vertical sectional view through one blade or scraper showing fragmentarily the chain hitch attached thereto.

Similar reference characters indicate corresponding parts throughout the several views in the drawings.

Referring to the drawings in detail, particularly Figures 1 to 3 inclusive, the machine comprises a pair of gathering or scraper blades 10 each being preferably curved inwardly toward its lowermost edge and has fixed thereto fore and aft coupling members 11 for the mounting of the blades in a manner presently described.

Disposed crosswise of the blade are front and rear bars or rods 12 and 13 respectively, the latter being shorter than said front bar 12 and both bars or rods 12 and 13 have adjustably fitted thereon blocks 14, each being adjustably held through the medium of set screws 15 carried thereby. The blocks are formed with depending circular shanks 16 engageable in correspondingly shaped sockets 17 in the members 11, the latter being fitted with set screws 18 which engage in grooves 19 formed in the shanks 16 circumferentially thereof and in this manner the blades 10 are adjustably and detachably coupled with the blocks 14.

Each block 14 is formed with a cavity or space 20 for accommodating a sector gear 21 splined or keyed to the laterally extending turning end 22 of a crank-like hanger 23 having a wheel spindle terminal 24 for accommodating a traction wheel 25. Detachably carried by the blocks 14 are housings 26 each forming a mounting for a worm screw 27 and the meshing thereof with the gear 21, the stem 28 of the screw 27 being extended vertically to the proper height and carries

a wheel head 29 for manual manipulation of the screw 27. It will be obvious that each shank 23 is independently adjustable with respect to the others and in this manner the blades 10 can be raised and lowered relative to the ground surface while the adjustment of the blocks 14 upon the bars or rods 12 and 13 permits the adjustment of said blades laterally either for positioning the same angled to each other with the forward or rear ends in proximity one to the other accordingly to the uses of the machine.

Arranged centrally of the machine to rest upon the front and rear bars or rods 12 and 13 is a platform 30 which carries near one end a clip 31 to embrace a bar or rod 12 or 13 and for terracing and ditching operation of the machine the platform 30 has its clip 31 embracing the longer bar or rod 12 at the front 20 of the machine and this platform serves as a stand for the driver or operator of the machine so that the control for raising and lowering the blades 10 may be manually operated therefrom.

Attached to the blades 10 at their inner sides adjacent to the front end is a chain hitch 32 for the draft of the machine.

In Figure 1 of the drawings the traction wheels 25 are shown disposed outside of the 30 position of the blades 10 in the machine and in this arrangement the machine is set for terracing purposes.

In Figure 4 of the drawings the wheels 25 are located inside with respect to the blades 35 10 and in this arrangement the machine is set for ditching purposes, it being understood of course that the chain hitch 32 under the arrangement in Figure 1 has the pull thereof from the inner side of the blades 10 while 40 in Figure 4 under the arrangement therein the chain hitch 32 has the pull from the outer side of said blades 10.

Now it will be apparent that the relative disposition of the blades 10 with respect to 45 each other may be altered by adjusting the blocks 14 on the bars or rods 12 and 13 and on manipulating the hand wheels 29 the cranks 23 for the wheels 25 can be angularly adjusted to regulate the lift or the raising and lowering of said blades 10.

On adjustment of the machine for rearranging it for terracing and ditching purposes certain parts, for example, the blades 10, are reversed and the draft also reversed 55 as will be clearly evident from Figures 1 and 4 of the drawings.

The range of lateral adjustment of the blades 10 is according to the length of the bars or rods 12 and 13 and the control for the 60 wheels 25 will regulate the raising and lowering of the blades 10 and these controls permit independent adjustments fore and aft of the machine.

What is claimed is:—

1. In a machine of the kind described,

spaced fore and aft rods, blocks adjustably connected to the rods, crank hangers swingingly mounted in the blocks, traction wheels on the crank hangers, gathering blades swingingly supported from the blocks, and means for vertically swinging the crank hangers.

2. In a machine of the kind described, spaced fore and aft rods, blocks adjustably connected to the rods, crank hangers swingingly mounted in the blocks, traction wheels on the crank hangers, gathering blades swingingly supported from the blocks, means for vertically swinging the crank hangers, and a platform arranged upon the rods intermediate of the location of the blades.

3. In a machine of the kind described, spaced fore and aft rods, blocks adjustably connected to the rods, crank hangers swingingly mounted in the blocks, traction wheels on the crank hangers, gathering blades swingingly supported from the blocks, means for vertically swinging the crank hangers, a platform arranged upon the rods intermediate of the location of the blades, and a chain hitch connected with the blades near one end of each of the same.

4. In a machine of the kind described, spaced fore and aft rods, blocks adjustably connected to the rods, crank hangers swingingly mounted in the blocks, traction wheels on the crank hangers, gathering blades swingingly supported from the blocks, means for vertically swinging the crank hangers, a platform arranged upon the rods intermediate of the location of the blades, a chain hitch connected with the blades near one end of each of the same, and means for clamping the platform to one of the rods.

5. In a machine of the kind described, spaced fore and aft rods, blocks adjustably connected to the rods, crank hangers swingingly mounted in the blocks, traction wheels on the crank hangers, gathering blades swingingly supported from the blocks, means for vertically swinging the crank hangers, a platform arranged upon the rods intermediate of the location of the blades, a chain hitch connected with the blades near one end of each of the same, means for clamping the platform to one of the rods, and means for securing the blades in their adjusted positions.

In testimony whereof I affix my signature.

HOYT M. MURPHY.
